UNITED STATES PATENT OFFICE.

EDWARD ELISHA KILBOURN, OF NEW BRUNSWICK, NEW JERSEY, ASSIGNOR
TO THE KILBOURN KNITTING MACHINE COMPANY, OF SAME PLACE.

CIRCULAR-KNITTING MACHINE.

SPECIFICATION forming part of Letters Patent No. 408,180, dated July 30, 1889.
Application filed June 14, 1887. Serial No. 241,243. (No model.)

To all whom it may concern:

Be it known that I, EDWARD ELISHA KILBOURN, of New Brunswick, in the county of Middlesex and State of New Jersey, have 5 made an invention of certain new and useful Improvements in Circular-Knitting Machines; and I do hereby declare that the following, in connection with the accompanying drawings, is a full, clear, and exact description and specification of the same.

This invention has reference to circular or cylinder knitting machines, in which the needles are combined in a ring series, so that the yarn may be fed to the needles by a continuous circular movement for the formation of successive rows of stitches or loops, and in which also the thread-guide may be moved to and fro for reciprocating work.

The invention consists of certain new combinations of mechanical devices, which are set forth in the claims at the close of this specification. In order that these may be fully understood, I have represented in the accompanying drawings and will proceed to describe 25 a circular or cylinder knitting machine embodying them in the form in which I prefer to embody them for the purpose of knitting stockings, it being understood that the mechanism may be varied to suit the views of different makers and users.

Figure 1 of said drawings represents a front view of the said machine without the needles. Fig. 2 represents a view of the rear of the same. Fig. 2* represents an end view 35 of the circularly-moving thread-guide. Fig. 3 represents a top view of the said machine. Fig. 4 represents a transverse section of the same through the axis of the needle-cylinder, some parts of the machine being represented in elevation. Fig. 5 represents a longitudinal section of the portion of the machine to the left of the axis of the knitting-cylinder, and Fig. 6 represents the corresponding longitudinal section of the other portion of the 40 machine to the right of said axis, both sections being through the axis of the knitting-cylinder. Fig. 5* represents a vertical transverse section of a part of the nosing and knitting cylinder, showing the pin and groove 45 hereinbefore referred to. Fig. 7 represents a

vertical transverse section of parts of the machine at the axis of the count-wheel, with some parts in elevation. Fig. 8 represents a central vertical section of the cam-cylinders. Fig. 8* represents a horizontal section of one 55 of them. Fig. 9 represents a view of the outside of one of the carriers of the machine, hereinafter described. Fig. 10 represents a view of the inside of the same; Fig. 11, a transverse section of the same, and Fig. 12 a 60 top view of the same. Fig. 11* represents a transverse section of the same with an alternative arrangement of the guide-groove. Fig. 13 is a top view of the clutch mechanism hereinafter described. Fig. 14 is a face view of 65 the ring and driver hereinafter described. Fig. 15 is a view of the back of one of the cog-wheels, showing one of the drivers. Figs. 16, 16*, and 17 are full-sized views of the needles used in the machine. Fig. 18 is a 70 view of a part of the count-wheel and of the driving-pawl thereof. Fig. 19 is a view of a part of the count-wheel and the latch operated by the same. Fig. 20 is a view of a part of one of the change-wheels and the latch operated thereby. Fig. 21 is a view of a part 75 of the holder of the latch-lever. Figs. 3*, 22, and 23 are views of parts of the belt-shipper devices. Fig. 24 represents a plan of parts of a modification of the mechanism. Fig. 25 80 represents a front view of the same, and Fig. 26 represents a partial cross-section thereof. Figs. 27, 28, 29, and 30 represent views of other modifications, as hereinafter described.

The said machine is adapted to knitting 85 stockings—such as half-hose—by the following operations: First, the leg is knit down to the heel by means of the whole circular series of needles and of a thread-guide, which delivers thread to the needles for the successive 90 rows of loops or stitches by a continuous circular movement; second, the narrowed portion of the heel is knitted by a part or gang of the circular series of needles being put out of operation, the remaining gang of the series 95 being operated in combination with a reciprocating thread-guide, and the outer needles of the gang at work being put out of operation automatically and in succession until the work is narrowed to the predetermined 100

extent; third, the widened portion of the heel is knitted by progressively putting the outer needles of the gang into operation with the reciprocating thread-guide until the work is widened to the predetermined extent; fourth, the straight portion of the foot of the stocking is knitted by putting the two gangs forming the entire circular series of needles into operation in connection with the circular moving thread-guide, as when the leg was knit; fifth, the narrowed portion of the toe is knit in the same manner as the corresponding portion of the heel; lastly, the widened portion of the toe is knit in the same manner as the widened portion of the heel.

The drawings of the machine represent it with its members in the proper relative conditions for operating with the reciprocating thread-guide; but as it is most convenient to describe first the construction and operation of the machine for circular work I will proceed in that manner.

The needles preferably used in the machine are latch-needles having pivoted latches of the usual construction, and the shank of each is secured to or made in one piece with a projection or nib, upon which cams act for the purpose of moving the needles. The needles are arranged in a circular series and are fitted to slide up and down in the grooves of the knitting-cylinder A and its nosing A'. I prefer that the circular series of needles shall not be moved bodily while in operation, and the said machine is constructed on this plan. I therefore cause the needles to move up and down by means of two cams, which (as shown in section at B B', Fig. 4, and in elevation at B B', Fig. 8) are arranged one above the other and secured to cam-cylinders B² B³, which are concentric with the series of needles and are fitted to turn around the knitting-cylinder A, the lower cam-cylinder B³ being supported by a ring bearing or support b, and the upper cam-cylinder B² being supported upon the lower. The lower cam-cylinder B³ is held in place by means of studs B⁶⁰, secured to the ring-bearing, which studs are received in a dovetailed groove b' of the cam-cylinder. One of these studs is shown at Fig. 6*. The upper cam-cylinder is held in place by means of screws b²³, whose heads are received in a groove b² of the upper cam-cylinder. One of these screws is shown at Fig. 6*. The upper cam-cylinder B² is employed, preferably, to operate the gang of needles, which are put bodily out of operation when the heel and toe of a stocking are knit, the lower cam-cylinder B³ being employed, preferably, to operate the gang of needles which are employed in combination with a reciprocating thread-guide to knit the heel and toe of the stocking. In order to adapt the needles to the positions of these cams, those needles C, Fig. 17, which are to be operated by the upper cam B have their nibs b⁴ arranged at the required distance from their heads to be operated by that cam for circular work, and those needles C', Fig. 16,

and C², Fig. 16*, which are to be operated by the cam B' during widening and narrowing, and which may be called the "gang of fashioning-needles," have their nibs b⁴ arranged at the required distance from their heads to be operated by that cam for both circular work and reciprocating work. The fashioning-needles C', Fig. 16, which are to be withdrawn and returned to the gang at work during narrowing and widening, are held out of the working positions in the gang when withdrawn (or raised too high to be operated by the cam B' when reciprocating) by means of a holder applied, preferably, beneath their lower ends, or the lower ends of their shanks or slides, as hereinafter described. Consequently the shanks b⁵, Fig. 16, of these fashioning-needles are made long and terminate in supplementary nibs or feet b⁶, which are adapted to rest on the said holders. All the needles are guided when moving lengthwise of their shanks by being fitted to slide in grooves of the knitting-cylinder A and its nosing A', which hold the needles in their proper relative positions. The nosing A' is not secured rigidly to the knitting-cylinder A, but is made adjustable by being fitted to slide up and down within it without being turned and by being supported upon a screwed ring A⁸, whose screw-threads engage with an internal screw of the knitting-cylinder, so that the said ring holds the nosing in the position to which it may be adjusted. By turning this screwed ring the nosing may be adjusted higher or lower to correspond with the lengths of the loops that are to be drawn down by the needles. The nosing A' is prevented from turning, preferably, by means of a pin and an upright groove, the pin being secured to and projecting radially from the nosing, as represented at Fig. 5^a, and the upright groove being formed in the inner side of the knitting-cylinder A. The upper cam-cylinder B² is fitted at its upper end with a ring, by which the needles are held in place, and this ring is made in segments b⁷, Fig. 3, which are held to the cam-cylinder by screws, so that a segment may be readily removed and replaced.

When the entire series of needles is operated for knitting straight circular work, (such as the leg of a stocking,) both cam-cylinders B² B³ are caused to revolve continuously and simultaneously, so that each needle of the entire circular series is caused in succession to move lengthwise to and fro as required to take yarn for the loop formed by it and to cast off the preceding loop or stitch. For this purpose the two cam-cylinders are then connected by gearing with the main driving-shaft D, to which the fast and loose belt-pulleys d d' for the driving-belt are secured. I prefer to make the connection between the lower cam-cylinder B³ and the main driving-shaft D by means of a main wheel e, secured to the lower cam-cylinder B³, the intermediate wheel e', fitted to turn on a stud e², the pinion e³, secured to the upper end of the up-

right shaft e^4 , the upright shaft e^4 , the beveled pinion e^5 , secured to the lower end of the upright shaft, the beveled wheel e^6 , gearing into the beveled pinion e^5 , the beveled pinion e^7 , connected with the beveled wheel e^6 and fitted to turn upon a shaft e^8 , and the beveled wheel e^9 , which is secured to the main driving-shaft D and revolves with it. When, therefore, the driving-pulley d is caused to revolve in the direction indicated by the arrow applied to it in Fig. 3, the lower cam-cylinder is caused to revolve continuously in the direction indicated by the arrow c , Fig. 3. The upper cam-cylinder B^2 is preferably caused to revolve by being connected with the lower cam-cylinder B^3 , and the most convenient mode of connecting the two cam-cylinders is by means of two drivers, the one having the form of a lug c' secured to the cam-cylinder B^3 , which receives its revolving movement directly from the main driving-shaft D , and the other driver being preferably a pivoted or latch lug c^2 secured to the other cam-cylinder B^2 . This mode of connecting the two cam-cylinders for circular work by drivers is advantageous, because the cam-cylinders can then be readily turned by hand independently of each other to place their cams in such positions that the heads of all the needles are level, as they should be when work is set onto them; also, because if the one cam-cylinder B^3 is turned backward it does not carry the other B^2 with it, and because when one of the drivers is movable relatively to the cam-cylinders the connection between the two is detachable and may at any time be temporarily severed, a latch-driver being turned upward for that purpose.

In order that yarn or thread may be fed to the entire circular series of needles when knitting circular work, the thread-guide E is provided. This thread-guide is connected with the upper cam-cylinder B^2 , so as to be revolved with it at the requisite distance in advance of the cams B and B' of the cam-cylinders B^2 and B^3 to deliver yarn to the needles in succession before the said cams operate upon their nibs to depress them. In order that this circularly-moving thread-guide E may be readily moved out of its operating position when the heel and toe of a stocking are to be knit, it is secured to a rocking stock f , Figs. 2 and 2*, pivoted in the standards f' , which connect it with the cam-cylinder B^2 , and in order that the circular thread-guide may be held securely either when in or when out of its operating position a locking device is provided for that purpose. I prefer that this locking device shall consist of a spring lock-latch f^2 , whose nib engages with an arm f^3 , projecting from the stock f of the circular thread-guide. When the circular thread-guide is out of its operating position, the lock-latch engages with the upper side of the end of said arm f^3 , as represented at Fig. 2*, and when the circular thread-guide is in its operating position the lock-latch f^2 en-

gages with the under side of the end of said arm f^3 .

In order that the latches of the needles may be kept from accidentally flying up when knitting circular work and that they may be positively thrown down, I have used the latch-guard f^4 , which is connected with the stock f of the circular thread-guide E , and therefore may be readily turned out of its operating position and turned into it, and may be locked in either position.

The heads of the needles work in combination with the nosing A' , by the position of the upper edge of which the tightness of the loops drawn by the needle-heads is determined, and the partitions of this nosing between the needles consist of hooks a , with which the loops engage, so that when the needle-heads are raised the loops of the work are held by the hooks and do not rise with the needles. I prefer that these hook-partitions should be so combined with the nosing that the inclined inner edges z , Fig. 6^a, of the shanks of the partitions are above the rim y of the nosing, because the loops which are cast off by the needles are then guided inward and downward by the said inclined edges and are out of the way of the needles when they are subsequently raised.

In order that reciprocating work as well as circular work may be knit by the same machine, provision is made for throwing out of operation all the needles that are not required for reciprocating work, which is effected by constructing these needles C , Fig. 17, as previously described, with their nibs adapted to operate in connection with one cam-cylinder only, and by disconnecting that cam-cylinder from the driving mechanism and permitting it to remain at rest. The remaining or fashioning needles, which constitute the gang for reciprocating work, are then operated by causing the other cam-cylinder to turn to and fro.

In the machine represented in the drawings the upper cam-cylinder B^2 is the one which is disconnected from the driving mechanism for reciprocating knitting, and in order that it and the needles which it controls may be held positively at rest during the production of reciprocating work it is combined with a locking device, (shown in Figs. 2, 3, and 4,) which consists, preferably, of a notched latch F , with which a locking-lug a' , secured to the cam-cylinder B^2 , engages. The locking-latch F is preferably arranged at the back of the knitting-cylinder, and the locking-lug is preferably arranged to correspond circumferentially with the middle of the cam B of the cam-cylinder to be locked, so that when it is locked the needles which are at rest are at the back of the machine.

In order that the locking-latch may be readily moved out of its locking position and held there and may be readily moved into its locking position, it is connected with a rock-shaft g , from which an arm projects. The end g' of this arm is inclined, as seen in Figs. 1 and

6, and is within the range of an arm G, secured to a second rock-shaft G³, to which a lever-handle G' is secured. By moving the lever-handle G' to the right hand the lever-arm G is removed from beneath the arm g' and the locking-latch is lowered into its locking position, and by subsequently moving the lever-handle G' to the left the lever-arm G is forced beneath the arm g' and the locking-latch is raised from its locking position and is held in that condition until the lever-handle G' is again moved to the right. The lever-handle G' thus controls the locking device of the cam-cylinder B².

15 If the extent of reciprocation of the cam-cylinder B³, which is to operate during the production of reciprocating work, is less than a whole revolution, it is not necessary to disconnect the detachable driving-connection afforded by the latch-driver c² when the cam-cylinder B² is locked and remains at rest, and in such case a fixed lug-driver may be substituted for the latch-driver; but when the extent of reciprocation of the cam-cylinder B³ is as great or greater than a whole revolution a disconnectible driving-connection is necessary, and when this consists of a latch-driver it is turned upward, and then the cam-cylinder B² is wholly disconnected from any driving mechanism of the machine and remains at rest, although the other cam-cylinder may be reciprocated a full revolution or more.

During reciprocating work I prefer to cause the cam-cylinder B³ to move to and fro by a portion of the same gearing which is used for causing it to move during circular work and to use supplementary gearing to complete the movement. In one of the machines which I have made to embody the greater part of the invention the same driving-shaft is used for both circular and reciprocating work; but I prefer to use a supplementary driving-shaft D' for reciprocating work and to connect so much of the gearing as is then used with that supplementary driving-shaft. This system of using two driving-shafts is attended with the advantage that each may be driven at the speed best adapted for the work to be done, the possible speed when circular knitting is being done being much greater than when the machine is doing reciprocating work. The portion of the main gearing previously described which is used in the said machine for reciprocating work consists of the main wheel e, the intermediate wheel e', the pinion e³, the upright shaft e⁴, the beveled pinion e⁵, and the beveled wheel e⁶. The other portion of the main gearing, which remains connected with the main driving-shaft, consists of the two wheels e⁷ e⁸. In order that the former portion may be reciprocated for reciprocating work, the beveled wheel e⁶ is not made fast to the beveled wheel e⁷, and the connection of the said beveled wheel e⁶ with the beveled wheel e⁷ for circular work is effected by means of disconnectible drivers, which consist, preferably, of two lugs h h', Fig. 13, one of which is secured

to the back of the beveled wheel e⁶, while the other lug is connected with the beveled wheel e⁷, which is driven by the driving-shaft D for circular work. This mode of connection permits the driven wheel e⁶ to be moved to and fro nearly a complete revolution without affecting the driving-shaft D. A further extent of reciprocation is obtained by securing the lug h to a hub h², upon which the beveled wheel e⁶ is fitted to turn, and by connecting this hub with the beveled wheel through the intervention of a notched collar h³, Figs. 13 and 14, upon the hub h², and a pin h⁴, secured to the beveled wheel e⁶. By making the notch of the said collar wider, so as to increase the play permitted between the ends of the notch and the pin h⁴ of the beveled wheel e⁶, the extent of reciprocation of that wheel may be increased to any extent required to operate the cam-cylinder of the gang of needles used for reciprocating work.

The supplementary driving-shaft D' is fitted with fast and loose pulleys d² d³, to which a driving-belt is applied, and when it is in operation it is caused to revolve continuously. In order to cause the portion of the main gearing above described and the lower cam-cylinder B³ to move to and fro by means of the continuously-revolving supplementary shaft D', the portion of the main gearing above described communicating with the beveled wheel e⁶ is connected with the supplementary shaft D' through the intervention of reciprocating gearing. In that form of this gearing which I prefer there is a reciprocating rack H, Figs. 2 and 3, and a pinion e¹⁰, which is driven by said rack, and is then connected with the beveled wheel e⁶. The stock of the reciprocating rack H is fitted to slide in bearings connected with the main frame, and it is connected by a connecting-rod H', Figs. 2 and 3, with a crank H², which is secured to the shaft H³, and this crank-shaft is connected with the supplementary driving-shaft D' by means of the beveled wheels e¹¹ e¹². In order that the said reciprocating gearing may be connected with and disconnected from the cam-cylinder B³, the connection is made through the intervention of a clutch I, Fig. 13, whose hub is fitted to slide upon the pinion-shaft e⁸, and is connected with it (so as to be turned by it) by means of a spline and groove of the usual construction. The clutch has a tooth i, which is fitted to engage in a notch formed in a collar i' of the hub of the wheel e⁶, and the portion of the main gearing connecting it with the cam-cylinder B³ and that cam-cylinder are caused to turn to and fro reciprocally by the continuous revolution of the supplementary driving-shaft D'.

In order that the clutch may be readily moved, its hub is connected with a clutch-shipper, one arm J of which is forked and engages in a groove of the clutch-hub I', while the other arm J' has the form of a handle by which the attendant can move the clutch. The two arms J J' are connected by a rock-

shaft J². In order that the clutch-tooth and clutch-notch may correspond when the upper cam-cylinder B² is locked, the several gear-wheels previously described are so proportioned that the wheel e⁶ makes one revolution for each revolution of the cam-cylinder B² when circular work is made.

During reciprocating work the yarn is fed to the gang of needles then at work by means of a supplementary thread-guide E', which is caused to move to and fro in a circular curve by a movement derived from that of the cam-cylinder B³ then operating. In order that this supplementary thread-guide E' may be moved out of the way while circular work is being done and may readily be put in position for reciprocating work, it is connected pivotally with a movable bracket-arm E', that is supported by a standard E⁸ at the back of the machine. The hub g³ of the bracket-arm is fitted to turn on the head of the standard, and is provided with a pin g⁴, passed through said hub, and arranged to engage with a hole in the collar g⁶ of the bracket-standard E⁸ when the bracket-arm is in the position to hold the pivoted shaft g⁵ of the supplementary thread-guide centrally over the series of needles in the knitting-cylinder. When the supplementary thread-guide is to be thrown out of operation, this pin is withdrawn and the bracket-arm with the thread-guide is swung backward, so as to remove the thread-guide from its operating position, and it may be held when so removed by engaging the pin in a second hole in the collar g⁶. As the supplementary thread-guide is caused to move in alternately reverse directions, a duplex latch-guard f⁵ is combined with it to keep the latches of the needles from accidentally flying up when knitting reciprocating work.

The supplementary thread-guide is represented in the drawings in its operating position, and it is then caused to reciprocate by means of a cam E³, Figs. 2 and 8*, secured to the collar of the lower cam-cylinder B³. The ends of this cam operate alternately upon the shank of the supplementary thread-guide, and in order that the supplementary thread-guide may stand at rest for a short period at each end of its reciprocating movement a spring-driver j, Fig. 5, is introduced between the cam E³ and the driving-arm E⁶ of the thread-guide, and stops E⁴ E⁵, Fig. 3, are applied to limit the reciprocating movement of the supplementary thread-guide. Thus when one end of the cam is driving the supplementary thread-guide to the right hand the stop E⁵ stops its movement at the proper time, and the spring-driver, yielding to the pressure of the oblique end of the cam, permits the cam to pass it. A corresponding operation takes place when the supplementary thread-guide is moved to the left hand and is stopped by the stop E⁴. In order that the yarn may be subjected to the proper tension, the thread-guide is fitted with a thread-tension regulator of one of the usual construc-

tions, and a spring thread-take-up j', Fig. 5, also is provided to take up and give out slack yarn, as is customary in the use of knitting-machines. That one of the usual constructions of thread-tension regulators which I have used with success is represented at E¹⁰, Figs. 1 and 5, and consists of a pin having a slotted head. The yarn is passed through the slot of the head of the pin, and the pin is turned more or less to make the yarn deviate more or less from a straight line or to encircle the pin more or less, as may be found necessary to produce the resistance to the free movement of the yarn required to produce the desired tension.

In order that the work may be narrowed while reciprocating work is being done, more or less (as required) of the needles at the sides of the gang of needles at work are successively moved out of their operating positions by raising them, and the needles are held out of the operating position until the widening of the work is to be effected. During widening the needles are released and are pulled back successively to their operating positions by depressing them. The needles are raised and depressed by means of pickers K, Figs. 9, 10, 11, and 12, one for each side of the gang of needles doing reciprocating work. Each of these pickers is fitted to slide up and down in a carrier L, which is moved as required to place the picker in the position to operate upon the required needle. Each carrier is fitted to turn concentrically with the series of needles, so that the pickers bear the same relationship to whichever needle they operate upon. For this purpose the lower edge of each carrier is fitted in a circular groove of the frame-work at k, Figs. 5 and 6, and the upper edge of each carrier is fitted in a circular groove at k', Figs. 5 and 6, in the under side of the ring-support b of the cam-cylinders, these grooves being concentric with the knitting-cylinder.

If preferred, the ends of the carriers may be grooved and the stationary grooves k k' may be replaced by circular ribs, as shown at k*, Fig. 11*.

In order that the same picker may be used to move the needle for narrowing out of its working position and to move it for widening into its working position, each picker is fitted with two lugs k² k³, Figs. 10 and 11, one of which k², acting beneath the needle-shank, pushes the needle out of its working position for narrowing, while the other k³, acting upon the second nib b⁶, Fig. 15, of the needle, pulls it back into its working position for widening. The pickers are caused to move to and fro by means of a reciprocating cam K', Figs. 4, 5, and 6, which is preferably fitted to turn upon the stock a² of the knitting-cylinder, and each picker K is provided with a pin k⁴, which fits in the cam-groove of said cam, so that the movement of the grades of the cam-groove upon said pin causes it and the picker to move up and down in the carrier L. The

picker-cam K' is caused to reciprocate by connecting it with the supplementary driving-shaft D' through the intervention of a cam. Thus the picker-cam has a ring-wheel k^5 secured to it, and the teeth of this wheel engage with those of a segment k^6 , Figs. 2, 3, and 4, which is fitted to vibrate upon a stud k^7 , secured to the frame-work of the machine. To this segment is secured a second segment n , whose teeth engage with those of a rack N , which is supported in guides and has its shank connected by a pin with an upright lever N' , whose lower end is pivoted to the frame-work of the machine. The lever N' has two projections $n^2 n^3$, Fig. 6, which are within the range of the two members $n^4 n^5$ of a cam N^2 , which is secured to the crank-shaft H^3 of the machine, which, as previously described, is in this machine driven by the supplementary driving-shaft D' . By reason of this connection of the picker-cam K' with the crank-shaft the picker-cam is caused to turn to and fro correspondingly with the reciprocations of the reciprocating thread-guide and at the required times to operate the pickers K .

The best time at which a needle can be moved out of operation for narrowing the work is in the interval of the knitting movement of the needle which occurs after the cam B' of the cam-cylinder B^3 , while being moved in the direction toward the side of the gang of needles at which the needle is to be raised, has passed by the nib of that needle and before the cam of the cam-cylinder B^3 is returned to the position of the nib of that needle. On the other hand, the needle which is to be moved into its operating position for widening the work must be moved there by the picker before the leading end point of the cam B' of the cam-cylinder B^3 reaches that needle. The members of the cam N^2 which operate the picker-cam K' and the picker-cam groove should therefore be so shaped as to move the pickers K at the said times, as above set forth.

When a needle is moved out of its operating position, it should be held positively from returning until it is again wanted for widening the work. This positive holding of the needle is effected in the machine represented in the drawings by means of the needle-holder m , Figs. 4, 9, 10, 11, and 12, one of which is used for each picker and is connected with the respective carrier L thereof. This needle-holder m consists, preferably, of a ring segment, which is supported at its outer edge by being fitted to move in a groove of the carrier L , and is supported at its inner edge in a groove formed by two collars m' , Fig. 4, of the knitting-cylinder. The needle-holder is movable in the carrier, and a spring m^3 , Fig. 9, is applied to move it independently of the carrier. When the carrier is moved in the direction of the arrow m^4 , Figs. 9 and 10, as hereinafter described, to place the picker in position to move a needle out of the working position, the end of the holder m is pressed lat-

erally against the shank of that needle, the spring m^3 yielding to permit the carrier to move without carrying the holder with it. Then when the needle is raised by the picker the holder-spring m^3 forces the needle-holder beneath the raised needle and holds it positively in its raised position. The circular extent of the needle-holder is sufficient to hold all the needles which are successively raised for narrowing the work. When the carrier is moved outward—that is, in the direction indicated by the arrow m^2 , Fig. 9, to place the picker in the position for drawing a needle into the working position for widening the work—the needle-holder is moved with the carrier by reason of the end of the slot m^5 , Fig. 9, in the carrier L , through which the needle-holder pin m^6 passes, bearing against that pin, and the holder is thereby moved from beneath the foot of the needle upon which the picker is to operate, thus releasing it.

In order that narrowing or widening may be effected, the carrier must be moved to an extent equal to the distance between the centers of two needles, so as to remove the picker held by the carrier from the needle upon which it has operated to the next needle in the gang. The machine represented in the drawings is adapted to knitting stocking heels and toes, in which the narrowing and widening at each side of the work is the same, and both the carriers m are moved equally, but are moved in alternate succession, so that the needles at opposite sides of the work may be moved or raised out of the working position, or depressed or moved into it in alternate succession. On the other hand, the carriers and pickers should not be moved while the needles upon which they are to operate are being moved by the cam B' of the cam-cylinder B^3 for knitting. Consequently after each carrier and its picker are moved they should remain at rest at intervals between their successive movements.

The alternating movement of the picker-carriers L , with an interval of rest after each carrying or shifting movement of the needle-picker, is effected by means of the driving-shaft, which operates or imparts motion to the cam-cylinder B^3 for reciprocating work, the combination between each carrier and the said driving-shaft D' being effected by inseparable combining mechanism, which, while imparting a positive and intermittent motion to each carrier from the constantly-revolving driving-shaft, does not contain any devices which are disconnectible or liable to separate while operating and which would leave the carrier free to be moved accidentally or would permit the carrier to miss being moved to the desired extent or to be overmoved by momentum. When my entire invention is used, the machine (as previously described) is fitted with two driving-shafts D and D' , and as in this case the supplementary driving-shaft D' is the one employed to operate the cam-cylinder B^3 for reciprocating work

the carriers L are combined with that driving-shaft. The inseparable combining mechanism which I prefer to use for this purpose is as follows: Each carrier L is fitted with a worm-segment l, which is engaged with a screw l', secured to a shaft l'', which is fitted to both turn and move endwise in its bearings. Each screw-shaft is fitted with a pinion l³, whose teeth engage with those of a wheel l⁴, which is a driving-wheel common to both screw-pinions l³ l³. This wheel l⁴ is caused to turn continuously during reciprocating knitting by connecting it by the gearing hereinafter described with the supplementary driving-shaft D', from which (as previously described) the reciprocating thread-guide E' receives its movement. The gearing between the screws l' l' and the supplementary driving-shaft is preferably so proportioned in the machine represented in the drawings that each screw is caused to revolve one-half of a revolution for each revolution of the crank-shaft H³, that imparts the reciprocating movement to the thread-guide E', and the pitch of the screws l' l' is double the pitch or gage of the needles in the series, so that a half-turn of the screw is sufficient to move the carrier which it controls and the picker of that carrier from one needle to the next in the series.

In order that the screws, although revolved continuously, may impart motion to the carriers at distinct periods, alternated with periods or intervals of rest of the carriers, during which the needles are knitting, each screw has an endwise movement imparted to it. This endwise movement is in the same direction as that in which the carrier is moved by the revolution of the screw during each period in which the carrier should be moved, so that during this period the carrier is moved by the conjoined turning of the screw and its endwise movement. The endwise movement is in the reverse direction to that in which the revolution of the screw tends to move the carrier during each interval of rest and is equal to the tendency of movement by the screw at that time, so that during the interval or period when the carrier is to remain at rest the endwise movement of the screw equals and counteracts the screwing movement, and consequently the carrier is not then moved, but remains at rest, notwithstanding the turning of the screw on its axis. These endwise movements of the screws l' may be imparted to them by cams, and I prefer to use two cams for each screw, and to arrange these in the form of cam-collars l⁵, Figs. 3 and 4, which protrude at the opposite sides of one of the bearings l⁶, in which the screw-shaft revolves. The screw-shafts are fitted with pins l⁷, which bear against the cam-collars l⁵ l⁵, so that as these pins move during the turning of the screws along the inclined faces of the cam-collars the screw-shaft l² and screw l' are caused to move endwise.

During the narrowing of the work the car-

rier is caused to move inward—that is, to approach the middle of the gang of needles then at work, in combination with the reciprocating thread-guide—and during the widening of the work the carrier is caused to move outward. In order that these movements in reverse directions may be obtained from the driving-shaft, while always revolving in the same direction, the screw driving-wheel l⁴ is connected with the supplementary driving-shaft D' of the machine represented in the drawings through the intervention of gearing, which comprises two racks, (or wheels 80 operating as racks,) which are moved alternately in opposite directions. Thus the screw driving-wheel l⁴, which is fitted to revolve upon a stud secured to the frame of the machine, has secured to its hub a beveled pinion l⁸, Fig. 4, whose teeth engage with a beveled wheel l⁹, whose hub l¹¹ is fitted to turn upon the cylindrical stock or shank a² of the knitting-cylinder A. A corresponding beveled wheel l¹⁰, having its teeth reversed, is also secured to the same hub l¹¹, so that the two beveled wheels l⁹ l¹⁰ turn simultaneously. At the side of the hub of these beveled wheels which is opposite to the beveled pinion l⁸ a second beveled pinion l¹² is arranged, and this beveled pinion is connected with the supplementary driving-shaft D' through the intervention of the wheel l¹³, secured to the hub of the beveled pinion l¹², the intermediate wheel l¹⁴, secured to the intermediate pinion l¹⁵, (shown in dotted lines in Fig. 2,) the pinion l¹⁶, (also shown in dotted lines in Fig. 2,) secured to the crank-shaft H³, and the beveled wheels e¹¹ e¹², which impart motion from the supplementary driving-shaft D' to the crank-shaft H. The diameter of the pinion l¹² is smaller than the space between the faces of the reverse beveled wheels l⁹ l¹⁰, so that it can operate in connection with one of said beveled wheels without touching the teeth of the other, and the shifting of the driving-pinion from one l⁹ of the two beveled wheels to the other l¹⁰, and vice versa, changes the direction in which the two are driven, thereby reversing the turning movement of the pinion l⁸ and of the screw driving-wheel l⁴ and of the screws l', and consequently reversing the direction in which the carriers L are moved by the screws.

In order that the driving-pinion may be shifted automatically from one wheel to the other, the hub of the driving-pinion l¹² and of the wheel l¹³, secured to that pinion l¹², is fitted to turn upon a stud l¹⁷, which is movable, it being held by an arm l¹⁸, which is fitted to swing upon the axis of the intermediate wheel l¹⁴ as a center of motion, so that the driving-pinion l¹² may be shifted from one beveled wheel l⁹ to the other without affecting the engagement of the teeth of the wheel l¹³ and pinion l¹⁵, through which motion is transmitted to the driving-pinion. The driving-pinion also is provided with a stud or roller l¹⁹, Fig. 4, and a rail l²⁰, upon which this

roller bears, is secured between the two wheels $l^9 l^{10}$ to their hub l^1 . Two segments l^{21} also are secured (preferably by screws, as represented in Fig. 5) between the wheels $l^9 l^{10}$, with the teeth of the segments corresponding with those of the wheels. Consequently when the driving-pinion impelling either of the two wheels l^9 or l^{10} causes the appropriate segment l^{21} to come into gear with the pinion-teeth l^{12} the pinion runs in the segment and shifts from one of the wheels $l^9 l^{10}$ to the other, and the end of the rail l^{20} is in the proper position to permit the stud or roller l^{19} of the driving-pinion l^{12} to pass around it during this shifting operation.

The extents of the portions of the wheels $l^9 l^{10}$ which are between the segments l^{21} , and which are operated by the driving-pinion l^{12} before shifting, determine the number of turns imparted to the carrier-screws l' , and consequently the number of times the carriers are moved, and the number of needles that are moved into operation during the widening of the work and the number that are moved out of operation during the narrowing of the work. As the wheels $l^9 l^{10}$ are moved alternately in opposite directions, they operate as racks having a reciprocating movement, and as they operate to change the direction in which the carriers are moved I denominate them "change-wheels" or "change-racks."

It will be noticed that the segments l^{21} , which connect the change-wheels or the portions of them acting as change-racks, are set behind or within the teeth of said change wheels or racks. This is an advantageous construction for several reasons. Thus it is convenient, because it permits the two bevelled wheels $l^9 l^{10}$, with their hub, to be readily cast in one piece. It also permits machines of the same pattern to be readily adapted to the widening and narrowing of work to a greater or less extent by setting the segments l^{21} farther apart or nearer together, thereby increasing or diminishing the extent of the change-racks between the two segments. In the machine which is represented in the drawings, also, the construction is advantageous, because it permits one l^9 of the same change-wheels to be used to operate the driven pinion l^8 , for as the segments l^{21} are at the inside points of the teeth of the wheel l^9 and of the pinion l^8 the said segments do not interfere with the said pinion, but pass by it in their reciprocating movements. When the segments l^{21} are secured to the change-wheels by screws or rivets, the change in their position may be readily effected by inserting the screws or rivets in screw-holes or rivet-holes, which are nearer together or farther apart in the change-wheels. When a change is made in the positions of the segments l^{21} , the length of the rail l^{20} must be correspondingly lengthened or shortened, as the segments are set farther apart or nearer together.

From the foregoing description it appears that each carrier is combined with the driving-shaft for reciprocating work through the intervention of the worm-segment l , the screw l' , the cam-collars l^5 , the change wheels or racks $l^9 l^{10}$, and the various cog-wheels and pinions which have been described to connect the change-wheels with the screw at one side of them and with the driving-shaft D' on the other side of the change-wheels, and it also appears that this combining mechanism is an inseparable train of mechanism or gearing, or, in other words, is at all times free of a disconnection of any of its members which would free the carrier from the control of the driving-shaft. Consequently the movement of the carrier is always positive and to the exact required extent to shift the picker from one needle to the next of the series, and there is no possibility of the carrier being shifted by accident, or of missing a movement, or of being moved to a greater extent than is required.

When the machine is narrowing or widening, it is desirable that the thread-guide which is then reciprocating should have its extent of motion varied to suit the less or greater extent of the narrowed or widened work. In order that this variation may be effected, the stops $E^4 E^5$ are combined with the picker-carriers L , so as to be moved with the latter, the most convenient mode of combining them being to connect the stops with the picker-carriers L by means of brackets $E^9 E^{10}$; hence whenever a picker-carrier is moved the corresponding stop is moved to vary the extent to which the reciprocating or supplementary thread-guide can be moved by its cam E^3 . If this part of the invention is not to be used, the stops $E^4 E^5$ may be connected immovably with the frame-work of the machine; but in this case the thread take-up is required to take up and let out materially more thread than is necessary when the said part of my invention is used. The practical effect of limiting the movement of the reciprocating thread-guide by stops and permitting the needle-cam B' , which is then reciprocating, to be moved past the thread-guide by the continued movement of its cam-cylinder B^3 is to transfer the reciprocating or supplementary thread-guide from one side to the other of the reciprocating needle-cam, so that the thread-guide is in advance of that cam in whichever direction the cam be moving. This transfer is important in a machine in which the work is narrowed or widened whether the stops $E^4 E^5$ be moved with the picker-carriers or be fixtures, because the transfer obviates the necessity of using switch-cams, which tend to break the needles, and which also permit a certain amount of freedom of movement of the needles, which is objectionable, particularly when the cylinder-nosing A' is constructed with hook-partitions a , for if, in consequence of such freedom, a needle should drop in ad-

vance of its proper time of movement the yarn would be unduly strained upon the hook-partitions.

In the usual operation of knitting-machines 5 of the class to which my invention appertains it is customary to stop the machine by shifting the driving-belt from the fast pulley to the loose pulley, and as the machine represented in the drawings has two sets of belt-pulleys d d' and d^2 d^3 a belt-shipper is provided for each set of belt-pulleys. The belt-shipper P for the belt-pulleys of the main driving-shaft D is connected with a slide-bar p , fitted to slide endwise in bearings in the frame of the machine, and the belt-shipper P' for the belt-pulleys of the supplementary driving-shaft D' is connected with a slide-bar p' , which also is fitted to slide in bearings in the frame of the machine. A spring is provided to shift each belt-shipper from the fast pulley to the loose pulley, the spring p^2 , Fig. 3*, for the belt-shipper for the main driving-shaft D being connected with its slide-rod p , and the spring p^3 for the belt-shipper for the supplementary driving-shaft D' being connected with its respective slide-rod p' . In order that each belt-shipper may be held in its position for holding the belt on the fast pulley, a spring-actuated holding-latch is provided, the holding-latch p^4 , Figs. 1 and 22, of the main driving-shaft belt-shipper P being fitted to engage with a lug s of its slide-rod p , and the holding-latch p^5 , Figs. 1 and 23, of the supplementary driving-shaft belt-shipper P' being fitted to engage with a lug s' of its slide-rod p' . When either of these holding-latches or holders is disengaged by the operator, the belt-shipper which it controls is freed and permitted to shift the appropriate driving-belt from the fast to the loose belt-pulley. As there are two driving-shafts in the machine represented in the drawings and one only is operating at a time, confusion might arise in the mind of the attendant as to which 40 of the two spring-holders was to be moved in case the machine was to be stopped suddenly and which belt-shipper was to be moved to put the machine again at work. To obviate any difficulty from this cause, both spring-holders and both shipper-rods are arranged to be operated by the same shipper-lever R , which is common to both belt-shippers, and a shifting device is provided to change or shift the positions of the connections between 45 the belt-shippers P P' and the shipper-lever R , so that the shipper-lever controls only the belt-shipper of the main driving-shaft D when circular work is being knit and controls only the belt-shipper of the supplementary driving-shaft D' when the reciprocating thread-guide is operated and narrowing and widening are being done.

The shifting device which I prefer to use consists of a pin s^4 , Figs. 22 and 23, which is carried by a rod S , that is fitted to move to and fro longitudinally, its end to which the pin s^4 is secured being guided by guide-

grooves formed, in this example, in the shipper-rods p p' , (or in one of them,) through which groove or grooves the pin s^4 protrudes. 70 The shifting-pin s^4 is movable in inclined slots formed in the connections with the belt-shippers P P' . These inclined slots s^2 and s^3 are preferably formed in hooks r' r^2 , which are pivotally connected with the shipper-rods 75 p p' , and the slots are inclined in reverse directions, as represented at Figs. 22 and 23, so that when this shifting-pin s^4 is moved in one direction, as indicated by the arrow s^5 , Fig. 23, it will raise one hook r' into a position for 80 engaging with the shipper-lever R and will depress the other hook r^2 , so that it cannot engage with the shipping-lever R . When the shifting-pin s^4 is moved in the reverse direction, the positions of the two hooks are 85 reversed. The same shipping-lever R is employed to release the spring holding-latches p^4 p^5 , its lower end being for that purpose fitted at its front and rear sides with transverse lugs s^6 , which extend under the bodies of the 90 two holding-latches p^4 p^5 , so that as these lugs rise by being turned with the shipping-lever on its fulcrum-stud the lug which is beneath the holding-latch that is engaged with its shipper slide-rod is raised to release that 95 slide-rod and its belt-shipper.

In order that the proper belt-shipper and its appurtenances may with certainty be operated by the shipper-lever, the slide-rod S of the shifting-pin s^4 , that controls the hooks r' 100 r^2 of the belt-shippers, is connected with one arm s^7 of the lock-lever G' , so that whenever that lock-lever is moved to permit the locking-latch F to secure the cam-cylinder B^2 , and consequently whenever the supplementary 105 driving-shaft D' is to impart reciprocating movements to the reciprocating thread-guide E' and to the cam-cylinder B^3 for reciprocating knitting, the shifting-pin s^4 raises the hook r' of the belt-shipper P' for the supplementary 110 driving-shaft D' and places the hook r^2 of the belt-shipper P for the main driving-shaft D out of the condition for engagement with the shipper-lever R . When, on the other hand, the lock-lever G' is moved 115 to disengage the locking-latch F and release the cam-cylinder B^2 , so that circular work may be knitted and the main driving-shaft D may be used, the shifting-pin is moved (by reason of its connection with the lock-lever) 120 to raise the hook r^2 of the belt-shipper P for the main driving-shaft D , and to place the hook r' of the belt-shipper for the supplementary driving-shaft D' out of the condition for engagement with the shipper-lever 125 R . By reason of the employment in the machine of the said belt-shipper mechanism the attendant is relieved of the necessity of thinking which of the two belt-shippers should be operated and the risk of putting the improper driving-shaft into operation or of not shifting the belt of the proper one is prevented. When the belt of the supplementary driving-shaft D' is shifted to stop the opera- 130

tion of the machine at the close of reciprocating work, it is expedient that the reciprocating movement of the cam-cylinder B^3 for reciprocating work should always be stopped with its cam in the same position, which for the machine represented in the drawings is that which the cam occupies when the crank H^2 (through which motion is transmitted to the cam-cylinder B^3 , that is used for reciprocating work) is in line with its connecting-rod H' , as represented in Fig. 2. The means which I prefer to use for this purpose consist of a stop-lever Q , which is pivoted to the frame of the machine, and a stop-cam Q' , (shown in dotted lines in Fig. 1,) which is secured to the crank-shaft H^3 , with the tooth of the cam in position to be stopped by the tooth of the stop-lever when the crank is in line with its connecting-rod. The stop-lever Q has a handle Q^2 , which protrudes through a slot in the top of the frame of the machine, so that the stop-lever may be readily reached by the attendant; but in order that this stop-lever may be readily disengaged from the stop-cam when reciprocating knitting is to be done, and that said lever may be put again in the stopping position when circular knitting is to be done, the stop-lever Q is connected with the lock-lever G' by means of a link q , connecting with an arm q' of the lock-lever rock-shaft G^3 , so that the attendant has to operate but one lever (the lock-lever) to lock or unlock the cam-cylinder B^2 , which is used only for circular work, and to move the stop-lever Q to stop or release the mechanism for reciprocating work.

It is expedient that the attendant should know without counting the number of rows of circular work that is knitted, so that the attendant may know when the operation of the machine should be changed from circular work to reciprocating work. It is also expedient that the machine should be automatically stopped when the requisite extent of circular work has been done. For these purposes I prefer to use a counting device, which is driven from the main driving-shaft D by gearing, so as to be moved slowly and progressively for each row of stitches of circular work that is knit. For this purpose I prefer to use a count-wheel T , which is combined with the main driving-shaft by differential gearing, as hereinafter described.

I also use an index-pin t , which is screwed into one of a series of division-holes t' , formed in said count-wheel, which is distant from the commencing or zero point of the division-holes as many holes as correspond with the rows of stitches to be knit. In order that this index-pin may stop circular knitting when the required number of rows of stitches have been knitted, the latch p^4 of the belt-shipper P is fitted with an arm t^2 in position to be moved by the index-pin t when the required number of rows of stitches have been knitted, so that the latch of the belt-shipper for the main driving-shaft will then be disengaged

and the belt will be shifted from the fast to the loose pulley by the spring p^2 , previously described, for that purpose.

In order that the count-wheel T may be readily adjusted, I prefer to cause it to be turned by means of a spring-actuated pawl t^3 , which engages with a series of ratchet-teeth t^4 , formed upon the rim of the count-wheel. Consequently the count-wheel may be readily adjusted by turning it by hand, the pawl being held out of engagement with the teeth of the count-wheel in case it is expedient to turn the latter backward.

The differential gear which I prefer to use to transmit a slow movement to the count-wheel consists, as shown in Figs. 5 and 7, of the two beveled facing-wheels U U' , the two beveled pinions U^2 U^3 , secured, respectively, to the wheels U U' , and the traveling pinion U^4 , geared simultaneously into the beveled pinions U^2 U^3 . The traveling pinion U^4 is pivoted to an arm U^5 , which projects from a sleeve that is fitted to turn upon the shaft U^6 of the count-wheel T , and has also the pawl-arm t^6 , Fig. 18, secured to it. The wheel U and pinion U^2 are fitted to turn loose upon the sleeve of the traveling pinion, being held in their proper positions by collars, and the wheel U' and pinion U^3 are fitted to turn loose on the shaft U^6 of the count-wheel. The two wheels U U' , with their pinions U^2 U^3 , are caused to turn simultaneously in reverse directions by means of a pinion U^7 , which is common to both and which is connected with the main driving-shaft through the intervention of the beveled wheels U^8 U^9 . The two pinions U^2 U^3 are differential pinions, one U^3 of them having one more tooth than the other. Consequently at each revolution of these two wheels the traveling pinion U^4 , with its sleeve, is caused to turn a small distance around the axis of the count-wheel and to move the count-wheel slowly with it by means of the pawl t^6 .

In order that reciprocating knitting may be stopped automatically when the carriers L have been moved the required number of times for the extent of narrowed and widened work, one of the change-wheels is combined with a stop. For this purpose I prefer to fit one of the change-wheels t^0 with a stop u , Fig. 20, of pin form, and the latch p^5 is provided with an arm u' in the position to be moved by said stop u when the movement of the carrier and reciprocating knitting are to be stopped. As the latch p^5 is automatically moved when its arm u' is moved, the shipper P' is released and is then moved by the spring previously described and shifts the belt from the fast pulley d^2 to the loose pulley d^3 .

In order that the lock-lever G' may be held in either position in which it is placed, it is connected with a spring V , Fig. 21, which tends to hold it when vibrated to the end of its movement in either direction, and is strained when the lever is moved from either of its extreme positions. The clutch-shipper

J also is connected with a spring V', Figs. 2, 5, and 13, which tends to hold it in each of its extreme positions, and is strained when the clutch is moved from either of its extreme 5 positions. The shipper-lever R is connected with a similar spring V², Figs. 3 and 23. As I prefer to use pull-springs for this purpose, each spring V and V² is connected with its appropriate lever through the intervention 10 of a curved link v, Figs. 21 and 23, which transmits the pull of the spring to the side of the lever opposite that at which the spring is located. The relative arrangement of the lever, link, and spring is such that when the 15 lever (G', for example) is in its mean position the point of connection of the link with the lever, the rocking axis of the lever, and the point of attachment of the butt-end of the spring are all in the same straight line, or 20 approximately so. When the several devices are in this central position, the distance between the butt-end of the spring and the point of connection of the link with the lever is longer than the distance between the same 25 two points is when the lever is at either of its extreme positions. Consequently when the lever is in either of them the spring holds it with a yielding force. The spring V' is connected with a lug which projects from the 30 lower arm J of the belt-shipper, as represented in Fig. 2 and in dotted lines in Fig. 13, the other end of said spring being connected with the frame of the machine, as shown in Figs. 2 and 5. The movement of the arm J from 35 either of its extreme positions toward its central position extends the spring. Consequently the spring tends to hold the arm in either of its extreme positions when placed there by the attendant.

40 When the above-described mechanism is employed to knit half-hose, it is most convenient to commence by knitting the leg, using the revolving or circular thread-guide E and the whole circular series of needles, the count- 45 wheel T being adjusted to determine the shifting of the driving-belt of the main driving-shaft, as previously described, when the required number of rows of stitches have been knitted. When the machine stops, the ma- 50 chine is set for knitting the heel of the stocking by the following operations, viz: The recipro- 55 cating mechanism is unlocked by moving the lock-lever G' to the right hand, which also (as previously described) shifts the shipper me- 60 chanism, so that the belt-shipper P' of the sup- 65 plementary driving-shaft D' is controlled by the shipper-lever R, and also releases the locking device F of the upper cam-cylinder B². Next the cam-cylinders are turned to the left by hand until the locking-lug a' of the upper cam-cylinder B² engages with the locking-latch F. Then the clutch I, Fig. 13, is shifted by the clutch-lever J', so that the gearing for transmitting movement to the lower cam-cylinder B³, which in the machine described is used for reciprocating work, is put in connection (as previously described) with the sup-

plementary driving-shaft D'. The circular thread-guide E also is pushed back and held out of its operating position, as previously 70 described, by the spring lock-latch f², the yarn being left unbroken. Lastly, the reciprocating thread-guide E' is put into its operating position, (as previously described,) and the yarn is conducted through it to the needles, 75 after which the machine is put at work by shifting the driving-belt from the loose pulley d³ to the fast pulley of the supplementary driving-shaft. The machine then proceeds to knit the heel of the stocking, first narrow- 80 ing the work and then widening it, as determined by the extent of the rack portions of the change-wheels l⁹ l¹⁰, as previously described. While the driving-pinion l¹² is passing the first of the two curved segments l¹¹, which in- 85 tervenes between the two rack portions of the change-wheels l⁹ l¹⁰, there is a period of practical rest in the movement of the carriers L, and during this period several rows of stitches of the same length are knitted at the center 90 of the heel. When the machine has completed the heel, the stop u releases the latch p⁵ of the belt-shipper P' of the supplementary driving-shaft, and the machine stops. Then the machine is restored to the condition for 95 circular knitting by the following operations, viz: The lock-lever G' is moved to the left hand to put the stop-lever Q in position to engage the stop-cam Q' for stopping the crank-shaft H³, and also to move the latch F and 100 unlock the upper cam-cylinder B², as previously described, and to shift the shipper-hooks r' r², as previously described. Then the supplementary driving-shaft D' is turned by hand until the stop-lever Q stops its move- 105 ment. Next the clutch-lever J' is moved (for- 110 ward) to move the clutch I and disconnect the cam-cylinder gearing from the supplementary driving-shaft D', after which the yarn used for reciprocating work is broken, and the re- 115 ciprocating thread-guide is loosened by moving the pin g⁴ and is swung out of the way. Lastly, the circular thread-guide E is pushed inward to its operating condition, in which it is held by the lock-latch f², whereupon, as the 120 yarn is already connected with the work, the machine may be started for circular knitting by moving the shipper-lever R, which then operates the belt-shipper P and effects the 125 shifting of the driving-belt from the loose pulley d³ to the fast pulley d of the main driv- ing-shaft D.

It is expedient that the thread or yarn for each thread-guide should be conducted to it from a fixed thread-guide at a higher level, 125 and that some suitable thread-tension should be employed to impart the desired tension to the thread or yarn before it is passed through each thread-guide.

I prefer to construct each needle-cam B¹³⁰ and B', Fig. 8, with a supplementary grade x, to give a supplementary downward movement to the needles after each has taken the requisite amount of thread or yarn to form a loop,

the practical effect of which is to tighten the loop of yarn taken from the thread-guide and insure the casting off of the last preceding loop from the needle. The needles whose 5 nibs are held by the preceding cam-grade x' hold the yarn sufficiently to prevent it from rendering from the thread-guide to increase the extent of the loop on the needle upon which the supplementary cam-grade x is acting.

It will be noticed, as shown in Fig. 8, that the upper cam-cylinder B^2 has a larger internal diameter than the lower cam-cylinder B^3 , while the internal faces of both cams B B' are, as shown in Fig. 4, at the same radial distance from the axis of the knitting-cylinder. I prefer to construct the cam-cylinders with this difference of diameter because the increased internal diameter of the upper cam-cylinder permits the easy withdrawal of a broken needle from the lower cam-cylinder and its replacement by a new needle at any part of the circumference of the cam-cylinders except those occupied by the cams. When 20 the upper cam-cylinder is constructed in this manner, the nibs of the needles which are operated by that cam-cylinder are made longer than the nibs of the needles that are operated by the lower cam-cylinder to adapt the former needles to the greater diameter of the 25 groove x^2 , Fig. 8, which receives the nibs when they are not being operated by the cam.

If the upper cam-cylinder is constructed of substantially the same internal diameter as the lower cam-cylinder, the former should have a vertical groove with proper means of closing it to permit the withdrawal of the needles from the lower cylinder.

The groove may be of dovetail form and 40 may be closed by a dovetailed closing piece or gate, as represented in plan at a^4 , Fig. 30. This gate will be prevented from rising during the operation of the machine by the ring-segments b^7 , previously described.

45 The lower cam-cylinder should in all cases be constructed with a gate or opening in the internal flange at its upper end to permit the needles to be removed and inserted, and I prefer to have this gate at the side of the 50 cam-cylinder opposite to the cam and about half an inch in breadth.

The hook-partitions a , Figs. 6 and 6 b , of the nosing hold down the work (as previously described) while the needles are rising. Their 55 combination with two cam-cylinders, both of which are used for circular work and one only of which is used for reciprocating work, is important, because while one cam-cylinder is at rest and the work is hanging on the needles which are controlled by that cam-cylinder and are at rest the needles which are being operated by the reciprocating cam-cylinder are knitting and are making the knit article longer at the side at which they work 60 than at the other side, which is held upon the needles that are at rest.

The aggregate number of teeth in the por-

tions of the change-wheels l^9 l^{10} operating as racks and in the curved segments l^{21} , connecting those rack portions, must be such relatively to the number of teeth in the shifting pinion l^{12} that when said pinion, after the widening and narrowing is completed, reaches the same part of the curved segment from which it started for narrowing, the crank H^2 (through which the reciprocating movements are transmitted to the reciprocating cam-cylinder) also reaches the position from which it started when the reciprocating movement of the cam-cylinder was commenced, which position of the crank is that in which it is represented at Fig. 2. The stop-pin u must also be in the proper position to permit the driving-shaft D' to stop a little before the crank reaches the said position, and the crank 75 can then be turned to that position by turning the driving-shaft by hand.

As it is desirable that the intervals or periods of rest of the picker-carriers should be longer than the periods during which 90 they are moved, the incline or grade of each cam-collar which is traversed by the pins of the screw-shaft during the intervals of rest is made longer in extent than the incline or grade which is traversed during the periods 95 in which the carriers are moved. For convenience of adjusting the positions of these cam-grades it is expedient that the cam-collars should be formed at the ends of sleeves which inclose the screw-shafts, pass through the 100 bearings l^6 of the screw-shafts, and can be moved in the bearings for adjustment, the sleeves when adjusted being made fast by means of set-screws, which are screwed through the sides of the bearings l^6 , as represented at Fig. 3.

Having thus described a circular-knitting machine embodying my invention in the best form in which I have embodied it previous to making application for a patent, I 110 wish it to be understood that the mechanism may be varied without ceasing to embody material parts of my invention, as some of the combinations recited in the claims may be omitted, while others are used. Thus, for 115 example, the change-racks may be straight instead of circular, and may be separate from the knitting-cylinder instead of being concentric with it. An example of this straight and 120 separate construction is represented at Figs. 24, 25, and 26. In this case the change-racks l^9 l^{10} are made in one piece with the segments l^{21} l^{21} , which connect them and are in the same plane, and a distinct set of cog-teeth l^{24} are employed to transmit motion to the pinion 125 l^8 . The driving-pinion l^{12} in this case, as in the machine first described, turns upon a stud l^{17} , which is held by an arm l^{18} , that is fitted to swing upon the axis of the intermediate wheel l^{14} as a center of shifting, so that the 130 driving-wheel may be shifted from one change-rack l^9 to the other l^{10} . The straight change-racks are guided by having their stock fitted to slide in guides, one of which is represented

at l^25 , Fig. 26, and each of which is supported in a bracket l^26 at the front of the machine.

The modifications of Figs. 24, 25, 26, 27, and 28 illustrate also the employment of a single or main driving-shaft for both circular work and reciprocating work, such main driving-shaft being then an equivalent for the supplementary driving-shaft D' of the machine first described. In this modification

10 the main driving-shaft D , the wheels $e^7 e^6$, and the clutch-hub I' correspond, respectively, with those of the machine first described, and these members are connected, when required, with the crank-shaft H^3 of the gearing for

15 reciprocating work through the intervention of a duplex clutch I and the connecting wheels and pinions $e^{20} e^{21} e^{22} e^{23}$, which in this case are arranged at the front of the machine. The duplex clutch I is connected with the

20 clutch-hub I' by a rod Z , which is fitted to slide in the shaft e^8 , is secured also at one end to that hub, and has a cross-pin at the other, which slides in slots in the shaft e^8 , while its ends project into an annular groove

25 in the interior of the sleeve of the duplex clutch I , the object of these slots and annular groove being to permit the clutch-hub I' (with which the rod Z and its cross-pin are connected) to be moved sufficiently to disengage and re-

30 engage the clutch-tooth i , Fig. 13, before the duplex clutch I is shifted by the movement of the same hub I' through the rod Z and its cross-pin. The duplex clutch is connected by a

35 spline z^2 and groove with the hub of the wheel e^7 , which is loose from the wheel e^6 , the loose connection between the wheels e^6 and e^7 being in this instance dispensed with. The duplex clutch has at one end a clutch-tooth i^2 , Fig. 28, which is fitted to engage in a notch

40 of the hub of the wheel e^6 , and has at its other end a clutch-tooth i^3 , Fig. 29, which is fitted to engage in a notch of the hub of the connecting-wheel e^{20} . When the rotation of

45 the driving-shaft D causes the wheel e^7 and the duplex clutch I to rotate, and when the members above described are in the positions in which they are respectively represented in

50 Figs. 27, 28, and 29, the duplex clutch I , being then connected, through the intervention of the connecting-wheels $e^{20} e^{21} e^{22} e^{23}$, with the crank-shaft H^3 , causes it to turn and operate the mechanism for reciprocating work, as previously described, the wheel e^6 being then caused to reciprocate (as previously described

55 with reference to the wheel e^6 of the first machine) and to transmit a reciprocating movement to the lower cam-cylinder B^3 . On the other hand, when the clutch-hub I' is shifted (as described with reference to the first ma-

60 chine) to disconnect the wheel e^6 from the crank-shaft and from the gearing operated by that crank-shaft for reciprocating work, the duplex clutch I is moved also in the direction of the arrow in Fig. 27, the effect of which is to

65 disconnect it from the connecting-wheels $e^{20} e^{21} e^{22} e^{23}$ and from the crank-shaft H^3 and to connect it directly with the wheel e^6 , where-

upon the wheel e^6 is caused to revolve continuously and to transmit a continuous circular movement to the cam-cylinders $B^2 B^3$ and to the other devices for circular work, as described with reference to the first machine, while the crank-shaft is then disconnected from the driving-shaft D and remains at rest.

In a machine modified as above described 75 the belt-shipping devices for one of the two driving-shafts of the first machine would be dispensed with, and also the stop device for acting upon those belt-shipping devices, and the belt-shipper of the main driving-shaft 80 would be released and permitted to shift the driving-belt, after the reciprocating work at any part of the stocking is completed, by means of a supplementary stop-pin applied in the proper hole of the count-wheel previously 85 described.

The members of the said Figs. 24, 25, and 26 which have not been herein described correspond, respectively, with those parts of the first machine which are designated by the 90 same letters.

The depressing or operative portions of the needle-cams are located at one side of the respective rings of which they form a part. As these cam-rings are movable independently 95 of each other, by turning the one which has its cam in engagement with its needles a half-revolution or less the needles of both series or gangs can be brought into a raised position at one time.

100 The hook-partitions for the knitting-cylinder, the thread-supplying devices, and the narrowing and widening devices form the subject-matter of my applications Nos. 310,077, 310,078, and 310,079, filed May 9, 1889, and are 105 not claimed herein.

What I claim, and desire to secure by Letters Patent, is—

1. The combination, substantially as before set forth, of the stationary knitting-cylinder, 110 the sliding nosing for said cylinder, and the screw-ring which holds said nosing.

2. The combination, substantially as before set forth, of the knitting-cylinder, two cam-cylinders fitted to turn simultaneously around 115 it, and the disconnectible drivers by which one cam-cylinder is driven from the other for continuous circular work, but which automatically permit one cam-cylinder to be reciprocated independently of the other for reciprocating work.

3. The combination, substantially as before set forth, of the knitting-cylinder, two cam-cylinders fitted to turn around it, and disconnectible drivers connecting the two cam-cylinders, whereby, when power is applied to move one of said cylinders continuously in the same direction, the two cylinders are caused to revolve simultaneously for circular work, and whereby one of them is permitted 130 to remain at rest while said other cam-cylinder is reciprocated a complete revolution for reciprocating work.

4. The combination, substantially as before

set forth, of the knitting-cylinder, the two cam-cylinders for operating the needles of the knitting-cylinder for knitting circular work, and the locking device for locking one of said cam-cylinders and rendering it temporarily inoperative while the other cam-cylinder is being caused to reciprocate.

5. The combination, substantially as before set forth, of the knitting-cylinder, two cam-cylinders for operating the needles thereof for circular work, the locking device for locking one cam-cylinder and rendering it inoperative during reciprocating work, and the lever-handle by means of which said locking device is controlled.

6. The combination, with a knitting-cylinder, of two cam-cylinders operating in connection therewith, two driving-shafts, gearing intermediate one of said shafts, and the cam-cylinders for imparting a circular movement to the latter, reciprocating gearing operated from the other driving-shaft, and means for throwing said reciprocating gearing into operative connection, whereby one of the cam-cylinders may be reciprocated.

7. The combination, substantially as before set forth, of the knitting-cylinder, two cam-cylinders for operating the needles thereof, a driving-shaft, and gearing for operating the cam-cylinders from said shaft for circular work, said gearing having drivers with provision for lost motion or play to permit reciprocating movement to be given to one of the cam-cylinders without reciprocating the driving-shaft.

8. The combination, substantially as before set forth, of the driving-shaft for circular work, the driven wheel caused to revolve thereby, the disconnectible drivers, the notched hub with which one of said drivers is connected, and the pin in said driven wheel.

9. The combination, substantially as before set forth, of the knitting-cylinder, the two cam-cylinders for operating the needles thereof for circular work, the driving-shaft for circular work, the supplementary driving-shaft for reciprocating work, the gearing which is used for both circular work and reciprocating work, and the clutch and reciprocating mechanism through the intervention of which said gearing is connected with and disconnected from said supplementary driving-shaft.

10. The combination, substantially as before set forth, of two driving-shafts which are operated successively, the two belt-shippers for the same, and a single shipping-lever and means for putting the same into operative connection with either of said shippers when desired.

11. The combination, substantially as before set forth, of two driving-shafts, two belt-shippers for the same, a single shipping-lever, and a shifting device by which but one of the two belt-shippers at a time is subjected to the control of the shipping-lever.

12. The combination, substantially as before set forth, of the knitting-cylinder, the cam-cylinder for operating a part of the needles thereof for reciprocating work, operating devices whereby said cylinder is reciprocated, and the stop-lever and cam-tooth for stopping the reciprocating movement of said cam-cylinder at a particular part of its movement.

13. The combination, substantially as before set forth, of a knitting-cylinder, two cam-cylinders for operating the needles of the same, operating devices whereby one of said cylinders may be reciprocated, and whereby, when desired, the two cylinders may be caused to rotate together continuously in one direction, a stop-lever, and cam-tooth for stopping the reciprocating movement of one of said cam-cylinders at a particular part of its movement, devices for locking one of said cylinders in a stationary position during the reciprocating movement of the other, and the lever which controls the locking and unlocking of the said cam-cylinder.

14. The combination, as before set forth, of the knitting-cylinder, a circular series of needles divided into two gangs, two cam-cylinders for operating the needles for circular work, one of said cam-cylinders operating one of said gangs of needles for reciprocating work, and the counting device which indicates the number of circular rows of stitches which have been knitted.

15. The combination, substantially as before set forth, of the knitting-cylinder, two cam-cylinders by which the needles thereof are operated for circular work, the counting devices which indicate the number of circular rows of stitches which have been knitted, the driving-shaft for circular work, the belt-shopper appertaining to said driving-shaft, and the belt-shopper latch of the driving-shaft for circular work.

16. The combination, substantially as before set forth, of the picker and its carrier, a revolving shaft, and intermediate mechanism, including the change-wheels and segments, through the intervention of which the carrier is caused to move in reverse directions, the latch of the belt-shopper appertaining to said shaft, and a stop through the intervention of which the said latch is disengaged.

17. The combination, substantially as before set forth, of the picker and its carrier, a driving-shaft, gearing intermediate said shaft and said carrier, including the change-wheels and segments among its members, a belt-shopper for said shaft and its connected latch, and a stop moving with the change-wheels and adapted to release said latch.

18. The combination, substantially as before set forth, of a needle-cylinder with two cam-cylinders, devices whereby said cam-cylinders are given a common operative rotation for knitting circular work, and devices whereby one of said cam-cylinders is given a recip-

roating movement independently of the other for operating the needles during the widening and narrowing of the work.

19. The combination, substantially as before set forth, of a knitting-cylinder having needles divided into two gangs, independently-movable cam-rings for operating each gang of needles, the operative portion of each cam being on one side of its cam-ring, where-
5 to by an independent movement of one of said cams in relation to the other will throw all of the needles into an elevated position.

20. The combination, substantially as before set forth, of the lower knitting-cylinder with the upper knitting-cylinder, constructed of larger internal diameter than the lower cylinder.

In witness whereof I have hereto set my hand this 6th day of June, 1887.

EDWARD ELISHA KILBOURN.
